[57] **CLAIM**

The ornamental design for device for retrieval and placement of golf balls and golf tees, as shown and described.

DESCRIPTION

FIG. 1 is a perspective view of device for retrieval and placement of golf balls and golf tees showing my design; FIG. 2 is a front elevation view thereof; FIG. 3 is a bottom view thereof; FIG. 4 is a left side elevation view thereof; FIG. 5 is a top view thereof; FIG. 6 is a right side elevation view thereof; FIG. 7 is a rear elevation view thereof; and, FIG. 8 is an auxiliary view taken along line 8—8 of FIG. 4.

The broken line showing of a portion of a hand held support shaft in the drawings is for illustrative purposes only and forms no part of the claimed design.
